DESIGN FOR LACE

James Waterfield, Philadelphia, Pa., assignor to Louis A. Silk & Company, Inc., New York,
N. Y.

Application January 4, 1936, Serial No. 60,410

Term of patent 3½ years

To all whom it may concern:

Be it known that James Waterfield, a citizen of the United States of America, residing at 5333 Wakefield Street, Philadelphia, in the county of Philadelphia and State of Pennsylvania, has invented a new, original, and ornamental Design for Lace, of which the following is a specification, reference being had to the accompanying drawing, forming a part thereof, in which the figure is a face view of a section of the lace showing my new design.

I claim:—

The ornamental design for lace substantially as shown and described.

In testimony whereof I affix my signature.

JAMES WATERFIELD,
